(57) **CLAIM**

The ornamental design for a binder with electronic display, as shown and described.

DESCRIPTION

FIG. 1 is a front perspective view of a first embodiment of a binder with electronic display showing my new design;

FIG. 2 is a bottom perspective view thereof;

FIG. 3 is a right side perspective view thereof;

FIG. 4 is a left side perspective view thereof;

FIG. 5 is a top perspective view thereof;

FIG. 6 is a front view thereof with the binder open lying flat;

FIG. 7 is a front perspective view of a second embodiment of a binder with electronic display;

FIG. 8 is a bottom perspective view thereof;

FIG. 9 is a right side perspective view thereof;

FIG. 10 is a left side perspective view thereof;

FIG. 11 is a top perspective view thereof; and,

FIG. 12 is a front view thereof with the binder open lying flat.

The broken line showing of interior details in FIGS. 1-3, 5, 7-9 and 11, and a clasp shown in FIGS. 6 and 12 is included for the purpose of showing environmental portions of the binder with electronic display and forms no part of the claimed design.

The equally spaced dashed lines shown in FIGS. 1-12 represent stitching.
